BIT GRINDING JIG

Paul R. Francis, Los Angeles, Calif., assignor to
 Alloy Steel & Metals Company, Los Angeles,
 Calif., a corporation of California

Application May 4, 1938, Serial No. 205,964

4 Claims. (Cl. 51—98)

This invention relates to a bit grinding jig, particularly useful in the grinding and sharpening of detachable rock drill bits of the type used in mining, quarrying and the like.

5 An object of my invention is to provide a bit grinding jig of the character stated, which is rapid, accurate and dependable in operation.

Another object is to provide a jig of the character stated which will sharpen bits of all makes 10 and sizes.

A feature of my invention is to provide a jig which will grind both the cutting edges and the gauge of the bit.

A further feature is to provide a jig which can 15 be easily mounted on a bench adjacent to any well known type of grinding wheel equipment, the standard type of wheel being sufficient to sharpen the bits; that is, the wheel need not be of any special form.

20 Other objects, advantages and features of invention may appear from the accompanying drawing, the subjoined detailed description and the appended claims.

In the drawing:

25 Figure 1 is an end view of the grinding jig in position adjacent the grinding wheel.

Figure 2 is a plan view of the same.

Figure 3 is a plan view similar to Figure 2, showing the bit in gauge grinding position.

30 Figure 4 is a side view of the mandrel guide socket.

Figure 5 is a bottom plan view of the bit mandrel guide.

Figure 6 is a side elevation of the bit mandrel guide.

Referring more particularly to the drawing, the bit grinding jig 1 is mounted on a bench or table adjacent the grinding wheel 2, which wheel is mounted on the usual arbor 3, rotated by a 40 suitable source of power not shown. The grinding wheel 2 is the usual and well known flat face type, and it will be noted that no special form of wheel is required to grind the bits when my jig is employed. The jig consists of a bed plate 4 which is bolted to the bench or table adjacent the grinding wheel 2 by means of bolts 5—5. A slide head 6 is mounted on the bed plate 4 and this head is adapted to be moved at right angles to the center line of the arbor 3. The slide head 45 is provided with an elongated slot 7, through which a clamp screw or stud bolt extends, and a clamp nut 8 screws onto the bolt or stud, thus holding the slide head in proper relation to the grinding wheel.

50 55 A pair of sockets 9, 10 are integrally formed

on the inner end of the slide 6, the center lines of these sockets are inclined downwardly and inwardly for purpose to be further described. For the purpose of grinding the cutting faces 11 of the bit 12, the bit is mounted as shown in Figures 5 1 and 2; a bit mandrel guide 13 is positioned in either of the sockets 9 or 10. The mandrel guide is a T shaped fitting and includes a post 14, which fits into either of the sockets 9 or 10. The sockets 9, 10 are each provided with notches 15 10 to receive the depending lug 16 on the lower part of the guide 13, thus the guide is non-rotatably held in the sockets. The bit 12 is attached to the outer end of a mandrel 17 and a handle 18 is attached to the mandrel for the purpose of holding 15 the bit against the grinding wheel 2.

The various cutting faces of the bit 12 are presented to the grinding wheel 2 by releasing the set screw 8 and sliding the head 6 back, and then again advancing the head so that the bit engages 20 the face of the grinding wheel, or by sliding the mandrel 17 in the guide 13.

For the purpose of grinding the gauge angle on the bits, the jig is used as shown in Figure 3. This consists of a slide head 19, which is slidably mounted on the bed plate 4, a stud extends through the slot 20 and a clamp screw 21 screws onto the stud and against the head 19, thus holding the head in proper position relative to the grinding wheel 2. The head 19 is provided with a vertical socket 22, into which a set screw 23 extends. A mandrel guide socket 24 is adapted to fit into the socket 22 and is held in position by the set screw 23. The post 14 of the mandrel guide 13 then fits into the socket 24, of the gauge, 35 thus the bit is ground as shown in Figure 3. The lugs 16 fit into the grooves 25 when the gauge grinding operation is in progress. The bit mandrel guide 13 is thus non-rotatably held in the socket 24 so that the bit will be held at a 40 proper angle to the face of the grinding wheel 2; the bit mandrel 17 can be rotated by the handle 18 so that the various blades of the bit can be carried against the face of the grinding wheel. The handle 18 provides a convenient hand hold 45 for the workmen while grinding the bit, as well as affording means of rotating the bit to various positions so that the cutting faces as well as the gauge can be ground.

Having described my invention, I claim: 50

1. A bit mandrel guide comprising a base, a pair of heads adjustably mounted on the base, said heads being substantially parallel, a pair of spaced sockets arranged on one of the heads, said sockets being inclined to the plane of the base, a 55

- bit mandrel guide being adapted to fit into either of the sockets, a mandrel on which a bit is mounted, said mandrel extending through the mandrel guide, a socket on the other head, an adapter fitting into the last named socket, means adjustably mounting the adapter in the last named socket, said mandrel guide fitting into the adapter when the gauge of the bit is ground.
2. A bit mandrel guide comprising a base, a pair of heads adjustably mounted on the base, said heads being substantially parallel, a pair of spaced sockets arranged on one of the heads, said sockets being inclined to the plane of the base, a mandrel guide being adapted to fit into either of the sockets, a mandrel on which a bit is mounted, said mandrel extending through the mandrel guide, a socket on the other head, an adapter fitting into the last named socket, means adjustably mounting the adapter in the last named socket, said mandrel guide fitting into the adapter when the gauge of the bit is ground, and means non-rotatably holding the mandrel guide in the sockets.
3. A bit mandrel guide comprising a base, a pair of heads adjustably mounted on the base, said heads being substantially parallel, a pair of spaced sockets on one of the heads, said sockets being inclined downwardly and inwardly, a bit

mandrel guide adapted to fit into either of the sockets, means rotatably holding the mandrel guide in the sockets, a mandrel on which a bit is mounted, said mandrel extending through the mandrel guide, a handle on the outer end of the mandrel, a vertical socket on the second head, an adapter fitting in the last named socket, a set screw in the socket bearing against the adapter, the mandrel guide being adapted to fit into the adapter, the means non-rotatably holding the mandrel guide in the adapter.

4. A bit grinding jig for bits having teeth, which are V-shaped in cross-section, the teeth being radially arranged on the bit, comprising a base, a head mounted on the base, a pair of sockets rising from the head, said sockets being arranged at an angle to the plane of the base, a bit mandrel guide removably mounted in a socket, a mandrel on which the bit is mounted, said mandrel extending through the mandrel guide and means non-rotatably holding the mandrel guide in a socket, a second head mounted on the base, a socket on the second head, an adapter fitting into the last-named socket, means adjustably mounting the adapter in the last-named socket, said mandrel guide fitting into the adapter when the gauge of the bit is ground.

PAUL R. FRANCIS.
